COLLAPSIBLE COT

Stephen J. Blaha, Hinsdale, Ill., assignor to The Rome Company, Inc., a corporation of New York

Application August 5, 1933, Serial No. 683,813

5 Claims. (Cl. 5—110)

The present invention has for its object to produce a cot or bed structure provided with simple and novel supporting means which will permit the same to be raised when in use and to be lowered when not in use.

Although not limited to this particular field, my invention is particularly applicable to so-called studio couches in which there is a rigid box-like structure that forms the couch proper, 10 and a low bed or cot that may be housed within the main structure when not in use. In the ordinary studio couch the auxiliary bed or cot is quite low and its height is only slightly increased by laying thereon a cushion or pad taken 15 from the top of the box-like structure. The removal of the cushion or the pad from the couch proper, of course, reduces the height of the latter so that, even though a double bed may be produced, the whole thereof is ordinarily too close 20 to the floor. Viewed in one of its aspects, the present invention may be said to have for its object to make it possible to convert a studio couch into a double bed or into two single beds the height of which is equal to the maximum 25 height of the couch. In other words, the invention may be said to have for its object to permit a studio couch to be converted into a double bed or into two single beds of uniform height, without reducing the height of the couch proper.

30 The various features of novelty whereby my invention is characterized will hereinafter be pointed out with particularity in the claims; but, for a full understanding of my invention and of its objects and advantages, reference may be had 35 to the following detailed description taken in connection with the accompanying drawings, wherein:

Figure 1 is a side view of my improved cot or bed in a raised position, ready for use, a fragment of the cover of the mattress-supporting spring being broken away; Fig. 2 is a bottom plan view of the cot, the mattress-supporting spring structure being omitted; Fig. 3 is a side view of a cot or bed, on a somewhat smaller scale than Figs. 1 and 2, showing the cot or bed in its lowered position; Fig. 4 is a top plan view of the cot as it appears in Fig. 3; Fig. 5 is an end view, on the same scale as Figs. 1 and 2, showing the cot as it appears in Fig. 1; and Fig. 6 is a section on line 6—6 of Fig. 1.

Referring to the drawings, 1 represents a suitable light metal frame carrying a suitable mattress support which, in the arrangement shown, is in the form of a bed spring containing vertical coil springs 2. Also, in the arrangement shown,

there is a fabric cover 3 extending over the mattress support to conceal the same. Overlying the mattress support is a suitable mattress or cushion 4. These parts may all be of any usual or suitable types and constructions; the particular arrangement that I have illustrated being intended only to serve the purpose of making clear the application of my invention to cots or beds.

The frame is supported upon four legs 5, 5 that may conveniently be pieces of channel iron fastened at their upper ends to the side bars of the frame by pins 6, 6 which serve as hinge pins. The two legs at each end are connected together, near their lower ends, by a cross bar 7 so that both swing as a single unit. The two leg units 15 may be folded up against the under side of the frame, as shown in Fig. 3, or they may be swung down into supporting positions, as shown in Fig. 1. When the leg units are in their supporting 20 positions they stand at an angle to each other, being farther apart at their lower ends than at their hinge pins. As it is at no time desirable that the leg units swing toward each other into upright positions or past such upright positions, I provide each leg with a projection 8 lying above 25 the hinge pin and adapted to strike against the under side of the frame before the leg units swing too far toward each other.

When the leg units are unfolded, as shown in Fig. 1, they do not of themselves hold up the bed structure but, unless assisted by other means, will permit that structure to drop again. The means to prevent the dropping of the bed structure, after it has been raised, consists of four levers 9, 9, two at each end of the structure, each leg and 35 the corresponding lever lying in the same vertical plane. In the arrangement shown, the levers are in the form of bell cranks each pinned to the side members of the cot frame, as indicated at 10, to swing about an axis parallel to the hinge axes 40 of the leg units. The inner end of each bell crank lever is provided with a wheel or roller 11 adapted to ride in the trough of the corresponding leg. The other end of each bell crank lever is adapted to engage with a stationary stop on the cot frame when the cot is raised. On one side of the frame the stationary stops are lugs 12 fixed to the frame and conveniently forming extensions of the end bars of the latter. On the other side of the frame, the stops may conveniently be 45 the hooks 13 by means of which the cot is adapted to be coupled to the body member of a studio couch. The pivot pins of each pair of bell crank levers lie between the adjacent end of the cot frame and the hinge axis of the corresponding 50 55

leg unit. Consequently, the weight of the bed or cot and its load, which acts in a direction to force the hinged ends of the leg units down, is prevented from causing the collapse of the structure because 5 a downward movement of the bed or cot structure cannot occur unless the contacting ends of the bell crank levers can be pushed out of the way. The bell crank levers cannot swing in one direction because they are engaged with stops, 10 and they cannot swing in the opposite direction because the load is imposed on the hinge or pivot pins 10 just as it is on the hinge pins 6. In other words, the inner ends of the bell crank levers extend inwardly and downwardly in such directions 15 that the angles between the same and the lower ends of the corresponding legs are no greater than a right angle; so that they must first be swung downward into such positions that these angles are greater than a right angle before 20 the upward pressure of the leg units thereon can have any effect in causing movements of the levers.

The inner ends of the two bell crank levers at each end of the structure are connected together 25 by a rod 14 which may serve also as the shaft or axle for the corresponding rollers 11. These rods are in turn connected together by a spring-held equalizing means. In the arrangement shown, this equalizing means consists of a transverse bar 30 15 underlying a cross member 16 placed at the middle of the frame 1; the bar 15 being pivoted at its middle to this cross member, as indicated at 17. From each end of the cross bar extends a long link 18 which is in turn connected to one of 35 the rods 14. Between each end of the cross bar 15 and the adjacent side member of the bed or cot frame is a strong tension spring 19, one end of which is connected to the cross bar and the other end to the frame. The springs are so placed that 40 they are under an initial tension when the cot is in its raised condition, and hold the cross bar 15 almost parallel with the transverse frame member 16. In order to swing the bell crank lever devices past center so as to permit the weight of the 45 structure to act in a direction to swing them out of the way of the leg units and enable the latter to fold up against the under side of the frame, it is necessary to stretch the springs. In other words, the bell crank lever devices are held in 50 the position shown in Fig. 1, after having been brought there, by the pull of the springs.

The bell crank levers are provided with extensions or arms 20 that are continued beyond the ends of the frame; the extensions or arms at 55 each end of the structure being connected together by a cross bar or rod 21 that serves as a handle and also as a means to hold down the mattress when swung up over the top of the same upon lowering or collapsing the structure, as 60 shown in Figs. 3 and 4.

The parts being in the position shown in Fig. 1, and it being desired to lower or collapse the structure, one of the handle bars is grasped and is pulled up with one hand while the other hand 65 is pressing down on the mattress. These combined forces result in swinging the bell crank lever devices away from the leg units so as to permit the latter to fold up against the under side of the frame as the frame descends; each leg being preferably provided at its lower end with a roller 22 to permit the lower end of each leg to roll along the floor as the lower ends of the leg units spread apart from each other during the lowering of the bed or cot structure.

70 It will be seen that the springs 19 are stretched

during the process of lowering the bed or cot so that energy is stored up in the same to lift the bed or cot when it is again desired to open or raise the latter. Therefore, when the bed or cot is to be raised or opened, one of the handles is 5 grasped and is pulled upwardly and outwardly toward the adjacent end of the bed or cot, the corresponding rollers 11 pressing down on the underlying leg unit and running along the same toward the hinge axis of the latter. During all 10 of this time the springs are exerting their pull which eventually results in the lifting of the bed structure. The bell crank devices at both ends of the structure, being connected by the equalizing means, move in unison with each other. 15 During the first part of the swinging movements of the bell crank units it is necessary to exert a moderate pull on the handle; but, as soon as the bell crank units have passed center, as it were, the springs exert a powerful effort and 20 complete the swinging of the bell crank units into the position shown in Fig. 1 and, consequently, complete the raising or opening of the bed or cot. At no time, however, either in the raising or in the lowering of the structure, is 25 it necessary to exert any great manual effort, and therefore the opening and the closing of the structure is simple and easy.

By properly proportioning the parts, the cot or bed may be caused to stand at the full height 30 of an ordinary couch or bed, when it is opened or raised, and yet be low enough, when closed or lowered, to be conveniently housed within the box portion of a studio couch or the like.

While I have illustrated and described with 35 particularity only a single preferred form of my invention, I do not desire to be limited to the exact structural details thus illustrated and described; but intend to cover all forms and arrangement which come within the definitions 40 of my invention constituting the appended claims.

I claim:

1. The combination with a frame, of leg devices hinged to the frame, interconnected lever mechanism including two levers pivoted to the frame near each end and outwardly from the corresponding leg devices, the inner end of each lever being adapted to rest on and ride along the adjacent leg device and swing it down when the inner end of the lever is swung up, a handle extending between and fixed to the outer ends of the levers at each end of the frame and spring means tending constantly to swing said levers in the directions to raise their inner ends.

2. The combination with a frame, of leg devices hinged to the frame and adapted to stand in downwardly and outwardly inclined positions at each end of the frame when the frame is elevated, interconnected lever mechanism including two levers pivoted to the frame near each end of the latter and outwardly from the corresponding leg devices, the inner end of each lever being adapted to rest on and ride freely along the outer inclined face of the adjacent leg device and swing it down when the inner end of the lever is swung up, stops on the frame adapted to engage with the levers and limit the upswinging movements thereof, and spring means tending constantly to swing said levers in a direction to raise their inner ends.

3. The combination with a frame, of leg devices hinged to the frame, interconnected lever mechanism including levers pivoted to the frame near each end and outwardly from the corresponding leg devices, the inner end of each lever

- being adapted to rest on and ride along the adjacent leg device and swing it down when the inner end of the lever is swung up, spring means tending constantly to swing said levers in the directions to raise their inner ends, the outer ends of the levers being extended far enough to project above a mattress on said frame when the levers are swung in directions to carry their outer ends inwardly, and a cross bar connecting together the extended outer ends of the levers at each end of the frame to serve as a handle and to hold the mattress when overlying the latter.
4. The combination with a frame, of leg devices hinged to the frame, interconnected lever mechanism including two levers pivoted to the frame near each end of the latter and outwardly from the corresponding leg devices, the inner end of each lever being adapted to rest on and ride along the adjacent leg device and swing it down when the inner end of the lever is swung up, stops to limit the swinging movements of the levers in directions to carry their inner ends up, the outer ends of the levers extending outwardly
5. The combination with a frame, of leg devices hinged to the frame, interconnected lever mechanism including two levers pivoted to the frame near each end of the latter and outwardly from the corresponding leg devices, the inner end of each lever being adapted to rest on and ride along the adjacent leg device and swing it down when the inner end of the lever is swung up, stops to limit the swinging movements of the levers in directions to carry their inner ends up, the outer ends of the levers extending outwardly
- 10
- 15
- 20

beyond the ends of said frame when the levers are in engagement with said stops, and spring means tending constantly to swing said levers in directions to raise their inner ends.

5. The combination with a frame, of leg devices hinged to the frame, interconnected lever mechanism including two levers pivoted to the frame near each end of the latter and outwardly from the corresponding leg devices, the inner end of each lever being adapted to rest on and ride along the adjacent leg device and swing it down when the inner end of the lever is swung up, stops to limit the swinging movements of the levers in directions to carry their inner ends up, the outer ends of the levers extending outwardly
